Des. 188,725
Patented Aug. 30, 1960

188,725

MAGAZINE FOR MAGNETIC RECORDING TAPE OR THE LIKE

John Pelham Wren, Swindon, England, assignor to The
Garrard Engineering and Manufacturing Company
Limited, Swindon, England, a company of Great
Britain

Filed Dec. 28, 1959, Ser. No. 58,826

Claims priority, application Great Britain Aug. 11, 1959

Term of patent 14 years

(Cl. D26—14)

Fig. 1.

Fig. 2.

Fig. 3.

Fig. 4.

Fig. 1 is a perspective view of a magazine for magnetic recording tape or the like, showing my new design, the face opposite that shown being substantially the same in appearance;

Fig. 2 is an enlarged side elevational view;

Fig. 3 is an enlarged front elevational view; and

Fig. 4 is an enlarged rear elevational view thereof.

I claim:

The ornamental design for a magazine for magnetic recording tape or the like, as shown and described.
